(57) CLAIM

The ornamental design for a scoop with long bag, as shown.

DESCRIPTION

FIG. 1 is a front perspective view of a scoop with long bag showing my new design;

FIG. 2 is a front perspective view thereof with the jam in an open position;

FIG. 3 is a front elevation view of FIG. 1;

FIG. 4 is a front elevation view of FIG. 2;

FIG. 5 is a rear elevation view of FIG. 1;

FIG. 6 is a rear elevation view of FIG. 2;

FIG. 7 is a left side elevation view of FIG. 1, the opposite side being a mirror image;

FIG. 8 is a left side elevation view of FIG. 2, the opposite side being a mirror image;

FIG. 9 is a top plan view of FIG. 1;

FIG. 10 is a top plan view of FIG. 2; and,

FIG. 11 is a bottom plan view of FIGS. 1 and 2.

The broken lines are for illustrative purposes only and form no part of the claimed design.
